UNITED STATES PATENT OFFICE.

WALTER D. HORNING, OF MILWAUKEE, WISCONSIN.

CONCRETE-MOLD.

1,233,878.

Specification of Letters Patent. Patented July 17, 1917.

Application filed December 9, 1913, Serial No. 805,572. Renewed May 9, 1917. Serial No. 167,580.

To all whom it may concern:

Be it known that I, WALTER D. HORNING, a citizen of the United States, and resident of Milwaukee, in the county of Milwaukee and State of Wisconsin, have invented certain new and useful Improvements in Concrete-Molds; and I do hereby declare that the following is a full, clear, and exact description thereof.

10 My invention refers to two-part molds for forming concrete pipe sections, the object being to provide a simple, economical and effective means for stripping the mold members from the completed pipe and for locking up said mold members.

15 With the above objects in view the invention consists in certain peculiarities of construction and combination of parts as set forth hereinafter with reference to the accompanying drawings and subsequently claimed.

In the drawings—

20 Figure 1 represents a side elevation of a mold embodying the features of my invention;

Fig. 2, a sectional elevation of the same, the section being indicated by line 2—2 of Figs. 1 and 3;

25 Fig. 3, a cross-section of the mold, the section being indicated by line 3—3 of Fig. 2, said cross-section illustrating the mold in its locked position and containing a pipe section;

Fig. 4, a cross-section of the mold showing the same partly open preparatory to stripping the completed pipe therefrom, and

Fig. 5, a similar cross-section of the partly open mold illustrating the position assumed by the stripper-plates prior to the molded pipe section being removed.

Referring by characters to the drawings, 1, 1', represent the two-part members of a mold, which together form a drum constituting the body of said mold. The upper edges of the mold members are capped by flared semi-circular heads 2, 2', and the lower edges are similarly capped by reinforcing angle-iron bands 3, 3'. The transverse edges of each mold member are reinforced by angle-iron strips 4, 4, 4', 4', the radial webs of which strips abut each other

to form tight joints when the mold members are closed. A pair of leaf-members 5 are secured to the body portion of the mold-member 1' adjacent to its angle-iron strips 4' for the reception of the ends of transversely disposed links 6. The opposite ends of each pair of links are in pivotal union with a bar 7, which bar, in conjunction with the set of links, forms a longitudinally disposed bail that is arranged to have horizontal swing. When the mold members are closed, the links 6 are adapted to seat into registered notches 6' that are formed in the radial flanges of the abutting angle-iron stay-strips 4, 4'. In this locked position the bar 7 is nested parallel with the longitudinal stay-strips juxtaposing the mold-section 1. Locking of the closed form is effected by set-screws 8 that pass through the bars 7 and 70 abut the adjacent flange of the angle-iron strip 4, the said set-screws constituting adjustable bail-engaging feet.

As best shown in Fig. 3, when the form is locked, the draw of the links 6 relative to 75 the point of contact of the bail-engaging feet, is to one side of an imaginary line intersecting the pivot-point of said links and hence the draw upon the oscillatory strip 7 is inwardly disposed. This inward 80 movement of the bar, however, is limited by engagement of the end of a handle 9, which handle is rigidly secured to said bar.

While I have described one of the mechanisms for locking the two-part mold together, it should be understood that both joints of said mold are provided with similar locking mechanisms as indicated in Fig. 2 of the drawings.

From the foregoing description it is obvious that when the mold members are registered, the operator swings the locking mechanisms across the joint, whereby the engaging feet or set-screws 8 will come in contact with the flange of the angle-iron strip 4 and 95 to lock up the mold a slight oscillatory movement of the handle 9 inwardly will cause the set screw points of contact to pass the center of draft, whereby the strain upon the links will hold the locking mechanism in 100 the position shown in Fig. 3.

It is also obvious that, by adjusting the

set-screws 8, any desired locking tension may be obtained, whereby the joint between the mold-members is rendered tight.

Under ordinary conditions the two-part mold-members are detached and separated from the green pipe section formed therein by bodily stripping said mold-members from the outer circular faces of the pipe section. This method of stripping the mold members 10 causes the outer surface of the pipe section to be marred or broken due to the fact that the vacuum and friction is of sufficient resistance to cause parts of the outer face of the pipe section to adhere to the mold. The 15 above method is also objectionable due to the fact that it requires considerable force to separate the mold surfaces from the pipe section and to overcome the above-referred-to objectionable features, I provide each 20 mold member with a thin sheet-metal circular stripping-plate 10. These stripping-plates are adapted to nest against the inner walls of the mold members and extend to a point adjacent to their longitudinal edges, 25 as best shown in Fig. 3. The stripping-plates have a certain percentage of elasticity and, when in their normal position, they assume a curve of less curvature than the mold section into which they are fitted, 30 which normal shape is shown in Fig. 5 of the drawings. Each circular stripping-plate 10 is arranged to have transversely disposed sliding play within its mold member and is confined by a bail 11, which bail 35 has inturned arms 11' extending through slots that are formed in the body of the mold member. The ends of these arms are riveted or otherwise secured to the stripping-plates, it being understood that the bail 40 is thus arranged in slidable union with the mold-member and positioned centrally with relation to its edges. By this arrangement the operator can conveniently manipulate the stripping-plates from the outside of the 45 mold-members when the latter are expanded.

As shown in Fig. 3, when a pipe section is being molded, the mold-members are closed about a hollow core 12, which core forms no part of my present invention, and thereafter 50 the concrete material is poured to form the hollow tile or pipe section and prior to pouring the material, it is understood that the stripping-plates are drawn outwardly by their respective bails to cause them to nest 55 snugly against the inner faces of their respective mold-members. After the pipe section has been completed and the material is set, the mold-members are separated as shown in Fig. 4. Thus it will be seen that 60 only a small surface of each mold-member is stripped from the surface of the green pipe section just formed. In this operation the stripping-plates serve as a guard and will adhere to the faces of the pipe section

due to adhesion and the length of the arms 65 11' of the bails will thus permit movement of the mold-members independent of said stripping-plates. The next operation is to remove the stripping-plates and this is effected by exerting downward pressure, 70 which pressure is applied to the bails, causing them to play in the shell slots. The effect of the pressure applied at the center of the stripping-plates will cause the outer edges of the same to move slightly away 75 from the surface of the pipe section, whereby air is admitted to thus break the vacuum and the said stripping-plates will then assume their normal positions, as shown in Fig. 5, or, in other words, their free edges 80 will gradually spring away from the surface of the pipe.

As shown in Figs. 1 and 4, in order to lock the spring metal stripping-plates in nested engagement with the molds, the bails 85 11 may be provided with eccentrics 12, whereby a positive drawing lock is effected.

I claim:

1. The combination of a two-part mold-member having apertures therein, bail-arms 90 extending through the apertures, and a flexible stripping-plate carried by the bail-arms adapted to conform to the inner surface of the mold-members.

2. The combination of a pair of semi-circular mold-members having apertures therein, a bail for each mold member provided with arms in slidable union with the apertures of said mold member, an arcuate resilient stripper plate secured to the arms 100 of each bail member, the stripper-plates being normally of less curvature than the mold members.

3. The combination of a pair of semicircular mold members having apertures therein, 105 a bail for each mold member provided with arms in slidable union with the apertures, an arcuate resilient stripper-plate secured to the arms of each bail, the stripper-plates being normally of less curvature than the 110 mold member, and means carried by each bail member engageable with the outer face of its associated mold member for drawing its related stripper-plate into engagement with the inner face of the aforesaid mold 115 member.

4. In combination, a mold member having a concave surface, a resilient stripper plate movably mounted in said mold member and adapted to fit against and conform to said 120 concave surface, said stripper plate tending to assume a shape of less curvature than that of such concave surface, and means for causing said stripper plate to conform to and fit against said concave surface.

5. A mold, comprising a combination of a plurality of mating mold members having coöperating concave surfaces, resilient strip-

per plates movably mounted in said mold members to form the molding surfaces and tending to assume a shape of different curvature from that of said concave surfaces, and
5 means for causing said stripper plates to independently conform to and fit against said concave surfaces.

In testimony that I claim the foregoing I

have hereunto set my hand at Milwaukee in the county of Milwaukee and State of Wis- 10 consin in the presence of two witnesses.
